UNITED STATES PATENT OFFICE.

ALBERT J. D. OHM, OF ASTORIA, NEW YORK, ASSIGNOR TO MAX SCHAFER CO., A CORPORATION OF NEW YORK.

DESIGN FOR A LANTERN LAMP.

Application filed March 17, 1923. Serial No. 5,501. Term of patent 3½ years.

To all whom it may concern:

Be it known that I, ALBERT J. D. OHM, a citizen of the United States of America, residing at Astoria, county of Queens, and State of New York, have invented a new, original, and ornamental Design for Lantern Lamps, of which the following is a specification, reference being had to the accompanying drawing, forming part thereof.

The figure is a perspective view of the lantern lamp.

I claim:—

The ornamental design for a lantern lamp as shown.

ALBERT J. D. OHM.

Witnesses:

JOSEPH T. McMAHON,
MAX D. ORDMANN.
